UNITED STATES PATENT OFFICE.

ALVIN L. BUFFINGTON, OF MINNEAPOLIS, MINNESOTA.

ACETYLENE-GAS LAMP.

SPECIFICATION forming part of Letters Patent No. 688,926, dated December 17, 1901.

Original application filed January 20, 1898, Serial No. 667,275. Divided and this application filed February 19, 1900. Serial No. 5,674. (No model.)

To all whom it may concern:

Be it known that I, ALVIN L. BUFFINGTON, a citizen of the United States, residing at Minneapolis, in the county of Hennepin and State of Minnesota, have invented certain new and useful Improvements in Acetylene-Gas Lamps; and I do hereby declare the following to be a full, clear, and exact description of the invention, such as will enable others skilled in the art to which it appertains to make and use the same.

My invention has for its immediate object to provide an improved acetylene-gas lamp especially adapted for use on bicycles; and to this end it consists of the novel devices and combinations of devices hereinafter described, and defined in the claim.

This case is filed as a division of my pending case, Serial No. 667,275, filed January 20, 1898, entitled "Acetylene-gas-generating lamp."

The preferred form of my invention, designed as a bicycle-lamp, is illustrated in the accompanying drawings. Therein like characters indicate like parts throughout the several views.

Figure 1 is a side elevation of my improved bicycle-lamp. Fig. 2 is a front elevation of the lamp. Fig. 3 is a vertical section taken on the line $x^3 x^3$ of Fig. 2, and Fig. 4 is a vertical section taken on the line $x^4 x^4$ of Fig. 3.

It will be noted that in the construction shown the lamp, taken as an entirety, forms a true or nearly true sphere or ball. A lamp having this exterior appearance I do not, of course, claim in this application, as the same is the proper subject-matter for a design patent.

The main body portion of the lamp is made up of a metallic zone a and a concentric cylindrical section a' , which is spaced apart inward of the same, but connected therewith at its ends to form a water-containing compartment a^2 . At its top the annular water-compartment a^2 is provided with a water-inlet passage a^3 , that is normally closed by means of a plug a^4 , provided with very small air-vents a^5 . The bottommost portions of the sections a and a' are connected, preferably near their central portions, by means of a thimble a^6 , that is provided with a screw-threaded

needle-valve b . Lateral perforations a^7 lead to the needle-point of the valve from the water-compartment a^2 , and a capillary passage a^8 leads from the needle-valve seat into the bottom of the cylindrical chamber or compartment formed within the cylindrical flange a' . The needle-valve b is provided with a spring-arm b' , by means of which it may be readily moved and which is bent to the outline of the exterior of the lamp and frictionally engages the same, so as to hold the valve b wherever set. The outer or forward end of the cylinder a' is closed by means of a concave web or plate c , that is either formed with a reflector on its face or covered with a removable concave reflector, (indicated at c'), but preferably provided with both, for reasons which will be hereinafter noted. The axis of this reflector or of the reflectors extends concentric to the axis of the cylinder a' and approximately in a horizontal direction, although this might of course be considerably varied. The concave plate c is provided at its center or axis with a perforated forwardly-projecting nipple c^2 , provided with a gas-burner c^3 . The perforated nipple c^2 and burner c^3 are so constructed that the gas which is forced therethrough and the burning flame therefrom will be projected forward approximately on the line of the axis of the reflector. The importance of this construction will be given further attention later on. It may be here noted that the passage through the nipple c^2 opens directly from an inwardly-projecting cap c^4 , provided with a multiplicity of capillary perforations c^5 in its peripheral wall.

d indicates a clamping-ring which has screw-threaded engagement with the outer and forward margin of the section a and is provided with an inturned flange which overlaps the edge of the reflector c' and removably secures the same.

The ring d carries a skeleton guard, formed by intersecting wires d' , which are bent so as to protect the flame from the burner c^3 and to complete the spherical form of the lamp.

d^2 indicates colored signal-buttons, preferably of blue or red glass, which are secured in the skeleton frame, one on each side of the burner.

The rear end of the cylinder a' is normally

- closed by means of an end piece f , which completes the spherical form of the rear portion of the lamp, and is provided with an inwardly-projecting flange f' , that has screw-threaded 5 engagement with the rear margin of said cylinder a' . A gasket or packing-ring f^2 is mounted in a suitable seat in the section f , outward of the flange f' , and engageable with the end of the portion which connects the sections a and a' . At its central portion the section f is provided with a rearwardly-projecting screw-threaded nipple f^3 , in which a ball socket or seat is formed.
- g indicates a stem which is provided at one end with a ball g' , which is held in its seat within the nipple f^3 by means of a perforated cap g^2 and screw-threaded onto said nipple f^3 . The other end of the stem g is secured to the frame of the bicycle in any suitable way.
- 20 The generating-chamber h , it will be noted, is formed within the cylinder a' between the concave front wall c and the rear section f . This carbid-holder, as shown, consists of two parts made up of alternate layers of perforated thin 25 metal and absorbent material extending over or approximately over the entire holder. I preferably place the perforated metal portions in direct contact with the carbid and surround the same with absorbent material.
- 30 k and k' indicate a pair of telescopically-engageable metal cups or sections which are perforated over their entire surfaces.
- k^2 indicates a third cup-like section which is perforated over its entire surface. This 35 section k^2 telescopes over the sections k and k' .
- k^3 indicates cloth or other absorbent material which is placed between the ends of the sections k and k^2 and the cylindrical sides of the sections k' and k^2 .
- 40 k^4 indicates a disk of cloth or other absorbent material which is pressed against the perforate end of the section k' , as shown, by means of a metallic disk n engaging the same and the coiled spring n' , compressed between 45 said disk n and the rear end section f .
- z indicates water contained in the annular water compartment or chamber a^2 , and z' indicates carbid contained within the carbid-holder. The carbid does not need to be granulated, but should be finely broken. It will be 50 noted that in the operative positions of the parts the lower peripheral portion of the carbid-holder stands directly over and in close contact with the feed-water passage a^8 .
- 55 By means of the ball-and-socket joint the lamp may be adjusted at any angle or turned in any position within, of course, its possible limit of movement permitted by the joint, and when the nut g^2 is tightened the lamp 60 will be securely held wherever set.
- To open up the generating-chamber, the lamp may be turned bodily, so as to unscrew the body of the same from the relatively-fixed section f . This of course gives ready access 65 to the interior of the generating-chamber, so that the carbid-holder may be removed, cleaned, refilled, and replaced in working po-

sition. The body of the lamp is of course secured to the section h by turning the same in reverse direction from that required to remove it.

The generating action is started by moving the valve b by means of the arm b' in the proper direction to open up the water-feed passage a^8 . As atmospherical pressure is rendered effective within the water-compartment a^2 , the water will be fed into the generating-chamber under a pressure equal to that of the column of water itself. The water which is fed into the generating-chamber will come 70 almost instantly into contact with the absorbent material and by the latter will, under the action of capillary attraction, be conducted completely around the carbid in the holder. When the generation is started, small particles only of the carbid and absorbent material will be in direct contact; but as the generating action proceeds the decomposed products will fill the perforations of the metallic sections, and thus greatly increase the direct 75 contact between the absorbent material and the contents of the holder. In this manner of giving increased contact between the absorbent material and the products of decomposition the increased resistance which the 80 water finds in reaching the carbid through the lime products is nearly or quite offset or compensated for by the increased direct contact between said lime products and the absorbent material. The gas which is generated 85 finds a ready escape through the perforations c^5 of the cap c^4 , and thence through the nipple c^2 and burner c^3 . The perforated cap c^4 will prevent any water which might possibly 90 by some contingency collect a considerable 95 quantity within the generating-chamber from being thrown into the nipple c^2 or burner c^3 under the vibrating movement of the bicycle. By projecting the flame on the axis of the reflector from a burner located at its center almost the entire reflecting-surface of the reflector is rendered effective, while with an ordinary vertically-projected flame a large portion 100 of the reflected rays are cut off or absorbed by the flame itself. I have also determined by experiment that a gas-flame will stand a much stronger wind when projected directly against the same than it will when 105 turned sidewise of the same. The flame which is turned sidewise or projected at approximately a right angle to the wind seems to be 110 extinguished, as if cut off. Furthermore, when the lamp is advanced rapidly in the direction of the axis of the reflector the wind which is caught by the concavity of the reflector seems to meet in a vortex near the burner, and thus either to rebound or to 115 resist the reverse force of the wind. The reflector must, therefore, be imperforate or practically imperforate, inasmuch as perforations 120 therein of any substantial size would permit a back draft through the reflector. Any material back draft through the reflector would 125 turn the flame backward under the advance 130

movement of the lamp and would either blow the same out or render the lamp inefficient.

The above features make the lamp especially adapted for use on a bicycle. I have 5 demonstrated that the lamp can be run at a highest possible bicycle speed with the burner unprotected or exposed, as shown, and even without the use of the skeleton guard, which, as a matter fact, is used more to prevent a 10 person from burning his hand or clothes than for any other purpose.

It will of course be understood that the features of construction above noted are capable of a very large range of variation.

15 What I claim, and desire to secure by Letters Patent of the United States, is as follows:

A portable gas-lamp, adapted for bicycle

and carriage use, which lamp has an unin- closed flame-chamber provided with a con- cave reflector set with its axis substantially 20 in a horizontal plane, and a gas-burner pro- jecting outward from the reflector with the axis of its tip substantially coincident with the axis of said reflector, the said reflector being free from any passages which would 25 permit back drafts therethrough, substan- tially as described.

In testimony whereof I affix my signature in presence of two witnesses.

ALVIN L. BUFFINGTON.
